UNITED STATES PATENT OFFICE.

JOSEPH LOCH, OF NEW YORK, N. Y.

PADLOCK.

SPECIFICATION forming part of Letters Patent No. 228,656, dated June 8, 1880.

Application filed September 15, 1879.

To all whom it may concern:

Be it known that I, JOSEPH LOCH, of the city, county, and State of New York, have invented a new and useful Improvement in Padlocks, which improvement is fully set forth in the following specification, reference being had to the accompanying drawings, in which—

Figure 1 represents a longitudinal section of my lock. Fig. 2 is a cross-section thereof in the line *xx*, Fig. 1; and Fig. 3 is a detail view of the plate which carries the locking mechanism.

Similar letters indicate corresponding parts.

This invention relates to improvements in padlocks; and the invention consists in a novel construction and arrangement of the locking mechanism and the shackle.

In the drawings, the letter A designates the shackle, and B the lock-case, the arms *c d* of the shackle having different lengths, and the lock-case having sockets *e f* to receive such arms.

The socket *e* receives the short arm *c* of the shackle, and its sides are solid, so that this socket is practically isolated from the interior of the lock-case or the mechanism contained therein, and no water is admitted to the case through this socket.

The socket *f* is open to the lock mechanism—that is to say, it has a hole, *g*, in which works the bolt *h*. To prevent the entrance of water to this socket *f*, and thence to the interior of the lock-case, I form a nipple, *i*, at the outer end of such socket, and arrange upon the long arm *d* of the shackle a cap, *j*, which takes its place upon the nipple when the shackle is in an inner position, as shown, thereby closing the socket.

The long arm *d* of the shackle is provided with a lateral socket, *K*, to receive the bolt *h* of the lock mechanism, which consists of the notched tumblers *l*, adapted to be displaced by a key, *m*, and work on pins *n*, arranged on the face of a plate, *O*, which is subjected to the action of a spring, *z*, having a tendency to hold the same in its locking position, and, further, of a projection, *p*, on the lock-case, corresponding to the notches of the tumblers,

and a spring-dog, *q*, acting on the tumblers. The dog *q* is mounted on a pivot, *v*, attached to the plate *O*, while the bolt *h* is fastened to such plate by a pivot, *w*, so that this plate carries the major portion of the lock mechanism—namely, all excepting the projection *p* on the lock-case. Said plate *O* is joined at its lower end to the back of the lock-case by a pivot, *y*, and when the proper key is inserted in the lock the tumblers *l* are thereby pushed inward against the action of the dog *q* until their notches are in a position to engage the projection *p*, when the plate *O*, with its attached parts, swings round on the pivot *y* against the action of the spring *z*, and the bolt *h* is retracted, so as to release the arm *d* of the shackle.

This lock mechanism is simple in its construction and readily applied to the lock.

By making the arms *c d* of different lengths the shackle may be moved out until the short arm *c* is withdrawn from its socket, and then the shackle may be turned or swung around on the long arm to free the hasp or other object fastened by the lock, leaving the long arm in its socket.

In the long arm *d* of the shackle is a groove, one part of which extends in a longitudinal direction, as at *r*, while another part, at the lower end of the longitudinal part, extends transversely, as at *s*. Into this groove is fitted a stop-pin, *t*, secured to the lock-case, and as the shackle *A* is moved in or out this pin works in the part *r* of the groove and allows a sufficient movement of the shackle to complete the withdrawal of the short arm *c* from its socket, while, when the shackle is in an outer position and is turned or swung around, as before stated, the pin enters the part *s* of the groove. In this manner the shackle *A* is allowed the required motion, but its detachment or complete withdrawal from the lock is prevented.

The long arm *d* of the shackle rests on a spiral spring, *u*, lying on the bottom of the socket *f*, and when the shackle *A* is pushed inward this spring is compressed, while when the shackle is released from the lock mechan-

ism it is moved or forced out by the action of the spring as far as the groove *r* and pin *d* allow.

What I claim as new, and desire to secure 5 by Letters Patent, is—

The combination, with the shackle *A*, of lock mechanism consisting of the bolt *h*, tumblers *l*, spring-dog *q*, pivoted supporting-plate *O*, and the projections *p* on the lock-case, all

constructed and adapted to operate substantially as described.

In testimony that I claim the foregoing I have hereunto set my hand and seal this 9th day of September, 1879.

JOSEPH LOCH. [L. S.]
